(57) **CLAIM**

The ornamental design for a solar candle, as shown and described.

DESCRIPTION

FIG. 1 is a perspective view of an embodiment of the solar candle of the subject disclosure;

FIG. 2 is a top plan view of the solar candle shown in FIG. 1;

FIG. 3 is a bottom plan view of the solar candle shown in FIG. 1;

FIG. 4 is a front elevation view of the solar candle shown in FIG. 1;

FIG. 5 is a back elevation view of the solar candle shown in FIG. 1;

FIG. 6 is a side elevation view of the solar candle shown in FIG. 1; and

FIG. 7 is a side elevation view of the solar candle of FIG. 1, shown from the side opposite that shown in FIG. 6.

FIG. 8 is a perspective view of another embodiment of the solar candle of the subject disclosure;

FIG. 9 is a top plan view of the solar candle shown in FIG. 8;

FIG. 10 is a bottom plan view of the solar candle shown in FIG. 8;

FIG. 11 is a front elevation view of the solar candle shown in FIG. 8;

FIG. 12 is a back elevation view of the solar candle shown in FIG. 8;

FIG. 13 is a side elevation view of the solar candle shown in FIG. 8; and,

FIG. 14 is a side elevation view of the solar candle of FIG. 8, shown from the side opposite that shown in FIG. 13.

The broken lines showing are for illustrative purposes only and do not form part of the claimed design.
